BIAXIAL SHOE

Harry Charles Stein, Yonkers, N. Y., assignor of one-fifth to Leonard J. Stein, Houston, Tex., one-fifth to Stanley M. Stein, New Orleans, La., one-fifth to Melvin Stein, Jackson Heights, N. Y., and one-fifth to Frank R. Stein, Yonkers, N. Y.

Application September 19, 1951; Serial No. 247,245

8 Claims. (Cl. 36—8.5)

1

My invention relates to shoes and shoe lasts and more particularly to shoes which are physiological in character. It is expected, thereby, to establish a closer equilibrium between the foot and its clothing than exists between the foot and its present type of covering.

While the problem of equilibrium has been recognized since 1819, when right and left shoes first made their appearance, little has been done thereafter for the preservation of foot function. Shoes have been corrective, rather than correct, and efforts have been largely confined to orthopedic shoes dealing with abnormalities of the foot.

As an example of improper equilibrium, the conventional shoe last for making shoes for the normal foot is built on a vertical axis passing centrally through the tibia. However, the vertical axis or the axis of weight bearing is through the calcaneus and is located from one to two centimeters lateral to that of the tibia.

Accordingly, the principal object of my invention is to provide a shoe last wherein the vertical axis of the heel coincides with the axis through the calcaneus, rather than through the tibia.

The conventional shoe last has a horizontal axis extending from its intersection with the vertical axis through the tibia to the region of the third metatarsal head. This position of the axis is intended to produce symmetry in the shoe. The axis of symmetry is in fact different from the two principal axes of the foot, which are the static or standing axis, and the dynamic axis, the axis of locomotion. Unless the calcaneus is centered to the heel of the shoe, there cannot be mechanical equilibrium between the foot and the shoe in either axis. It is, therefore, a further object to provide correct static and dynamic axes for the shoe and last which more nearly correspond to the bio-mechanic demands of the foot.

The dynamic axis I have determined extends medially oblique from the laterally positioned calcaneus, to the medially positioned ball of the big toe. Accordingly another object of my invention comprises the realignment of the axis of the conventional heel and toe sections to the dynamic axis.

Further objects include the re-location of the peaks of the longitudinal arches medially and laterally; the corresponding shift in the anterior transverse metatarsal arch region; and the other changes made necessary to insure the smooth forward transfer of the forces of locomotion

2

along the course of the dynamically loaded axis. I accomplish these and additional objectives and obtain my new results, as will be apparent from the shoe and last described in the following specification, particularly pointed out in the attached claims, and illustrated in the accompanying drawing, in which:

Fig. 1 is a posterior elevational view of the bones of the right foot, indicating the eccentricity existing between the axis of weight and the axis of bearing.

Fig. 2 is a plan view of a conventional military right shoe last arbitrarily divided into toe, body and heel sections.

Fig. 3 is a similar view, illustrating a lateral shift in the heel section made pursuant to my teachings, the original position being shown in the dot-dash lines.

Fig. 4 illustrates the same view, the position of the original last being shown in dot-dash lines, with angulation imposed on the heel section to place it in the dynamic axis, the toe section repositioned accordingly, and all refashioned into a new last.

Fig. 5 is a longitudinally sectioned view of the right shoe and last viewed medially.

Fig. 6 is a partial sectioned view thereof, taken along the plane 6—6 and in an anterior direction.

Fig. 7 is a partial view taken in the vicinity of the scaphoid bone, namely in the plane 7—7.

Fig. 8 is a similar view taken in the plane 8—8.

Fig. 9 is a transverse sectional view of a shoe in which the heel is provided with a lateral extension.

Fig. 10 is a partial side elevation of a shoe employing a modified form of a shank wedge.

Fig. 11 is a plan view of the same.

In Fig. 1 of the drawings, I have diagrammatically shown in a posterior view, the bones of the right foot, illustrating the lateral eccentricity existing between the axis of bearing through the calcaneus, and the axis of weight positioned centrally through the tibia. Depending on the age of the individual and other factors, this eccentricity varies from approximately one to two centimeters, and is indicated as e.

In Fig. 2, there is indicated a plan view of a right conventional military shoe last 10, diagrammatically divided for convenience into body, heel and toe sections 11, 12 and 13, respectively. The upright axis of weight through the tibia is indicated by w and the axis of bearing through the calcaneus, actually the medial

calcaneal tubercle, is indicated by *b*. The horizontal axis, or the axis of symmetry for the conventional shoe last, is *s*, passing through the axis of weight and the region of the third metatarsal head.

I overcome the instability of the conventional shoe and last brought about by the failure to recognize the aforementioned lateral eccentricity of the calcaneus with respect to the ankle bone, by a number of changes starting with a lateral shift of from one to two centimeters in the heel section. This is indicated diagrammatically by the new heel position shown in solid lines, or *12c* in Fig. 3.

Since the calcaneus, or heel bone, dominates the action of the entire foot, and must be equilibrated with the shoe to insure maximum function, I have, by my compensation, co-axially centered and aligned the calcaneus with the heel of the shoe. A shoe with a heel so positioned, enables the calcaneus to correctly receive and evenly redistribute the load of the body weight.

The calcaneus forms the posterior pier of both the medial and lateral longitudinal arches which serve to direct the streams of force toward the great toe when the individual is walking, or along the dynamically loaded axis *L*. Accordingly, I propose to angulate the transposed section of the heel into its new position *12d* to face squarely the ball of the great toe.

In order to establish the dynamically loaded axis, full provision must be made for unimpaired function of the great toe in its final discharge of force from the ground, referred to as the "toe snap." The forepart of the shoe last or toe section *13* is therefore reconstructed in the dynamically loaded axis or in the position indicated as *13d*.

There is thus provided ample space for unimpaired great toe function without any deflection, an important factor since the slightest deflection along the course of the great toe greatly impairs the complete fulfillment of its function.

The original body section *11*, which becomes the central portion of the last, is contoured to smoothly merge with the re-constituted toe and heel sections by filling it at points *f* and *g* and cutting away at points *h* and *j* to complete the outline of the final shoe last *10d*.

The establishment of the dynamically loaded axis *L* requires a re-alignment of the longitudinal arches. As shown in Fig. 5, I establish the longitudinal arch *14* in the shoe last with its peak *14d* located approximately at the level of the ligamentous junction of the calcaneus with the scaphoid bone on the medial side and at the level *15d* of the junction with the cuboid bone on the lateral side as shown in Fig. 6. The peak is considerably lower and positioned posteriorly of the peak *14a* in the present type of shoe shown in dot-dash lines in Fig. 5. It is higher toward the medial side as shown in Fig. 6, and somewhat more distally located on the lateral side.

The posterior pillar *16d* of the longitudinal arch *14* extends from the peak *14d* posteriorly to the region of the inferior medial calcaneal tubercle shown at about *17d* as a short slope, rounded, as at *18d*, as it passes under the region of the medial tubercle which forms its pier, as indicated in Fig. 5. The sloping of the pillar *16d* is somewhat lower and longer on the lateral side.

The anterior pillar *19d* of the longitudinal arch portion extends in a longer and more gradual slope from the peaks *14d* and *15d* to the head

of the first metatarsal bone on the medial side and the head of the fifth metatarsal bone on the lateral side. The lateral side is somewhat shorter.

An important aspect of the longitudinal arch is the provision in the medial margin of the shoe *20* of the compartment *20d* and between the innersole *20e* and the sides *20f*, for the downward projection of the tubercle of the scaphoid bone. The scaphoid is the key bone through which is distributed the stream of forces that go through the medial longitudinal arch, and the present invention accommodates the scaphoid and frees it from the disturbances present in the conventional shoe.

A further change in the construction of the conventional last and shoe, comprises the reversal of the trough or hammock like arrangement in the toe section of the shoe caused by curving the lateral margins upward along the edges, as indicated by the dot-dash lines *13a* of Fig. 8. Such trough causes a side rocker effect and results in a central concentration of force of the metatarsal heads, and in the failure to obtain a proper progressive distribution of weight towards the great toe.

In my last and shoe, the lateral margins *20g* of the sole portion lie flat, and the base *20h* thereof, is slightly elevated under the middle metatarsal head region.

Specific improvements are provided in the external shoe, such as the shank wedge, the sole wedge, and the lateral extension of the heel.

The shank wedge *22* is shown in Fig. 5 in section in Fig. 7, in elevation in Fig. 5, and its plan view position indicated in Fig. 4 by the dotted lines. This wedge, providing a counter-balancing support for the foot, is positioned externally along the lateral half of the outer sole *20j*, substantially lateral to the dynamic axis to facilitate the rapid transition from the static to the dynamic loading. The static axis extends from the axis of bearing through the calcaneus to the region of the third metatarsal head. The wedge extends short of the adjacent margin of the anterior outer heel *12k* to preserve the flexibility of the shank at this point. This same effect may be obtained by means of a steel spring *23*, incorporated in the sole of the shoe in the same location as the wedge and supported at its proximal end on an external underlying solid pier *24*, as is illustrated in Figs. 10 and 11, or by the pier itself, if the innersole or shank of the shoe is sufficiently resilient.

The sole wedge *25* is provided at the lateral margin behind the bases of the outer toes to act as a counter-support and a guide for the transfer of the forces involved in locomotion along the dynamically loaded axis, even when on toes. Its position is shown in dotted lines in Fig. 4, and in elevation in Fig. 5.

The eccentricity *e* between the upright axis of weight and the axis of bearing through the calcaneus may be partially accommodated in a modification of the present conventional shoe by an unyielding lateral extension *12L* in the outer heel, as shown in Fig. 9. This extension will establish co-axial centering of the calcaneus in the conventional shoe or secure if so desired, a therapeutic over-correction of the co-axially centering involved in the fully correct shoe previously described. Such heel may be entirely moved laterally as indicated by the dot-dash lines *12g*, or angulated after lateral movement in the amount *e* as shown in Fig. 4.

One or more of the above described features of my invention may be applied to innersoles, separate arches, slippers, tennis shoes, sandals, rubbers, bath shoes, shoe trees, and various types of footwear.

In the foregoing invention I have established the relationship between the shoe and the kinetics of the foot as viewed from an engineering point of view. The problem of equilibrium between the shoe and the foot, springs from faulty alignment. In my correct or physiological shoe, as I have termed it, I have established new axes in the shoe for both static and dynamic loads. I have re-established the congruity of the arches of the shoe with the skeletal arches. I have eliminated the rocker bottom involving the transverse axis of the sole, and have established a proper balance and counterbalance in the transverse plane. I have also provided auxiliary supports, and a stabilizing mechanism to guide unhindered the forward progression of the forces of gait along the dynamically loaded axis. In so doing, I have avoided undue strain of the foot, with its resulting breakdown and faulty and unnatural wear of the shoe.

I have thus described my invention, but I desire it understood that it is not confined to the particular forms or uses shown and described, the same being merely illustrative, and that the invention may be carried out in other ways without departing from the spirit of my invention, and, therefore, I claim broadly the right to employ all equivalent instrumentalities coming within the scope of the appended claims, and by means of which, objects of my invention are attained and new results accomplished, as it is obvious that the particular embodiments herein shown and described are only some of the many that can be employed to attain these objects and accomplish these results.

What I claim and desire to secure by Letters Patent, is as follows:

1. A shoe comprising a central portion having a longitudinal axis extending from the region of the center of the ankle through the third metatarsal head region, and a level heel for supporting the foot in an upright position having an unyielding laterally extending projection extending from the front lateral end of the heel to approximately the middle of the rear end of the heel, said projection at approximately the middle exterior side being equal in distance to the eccentricity of the calcaneal tubercle.

2. A shoe comprising a central portion having a longitudinal axis extending from the region of the center of the ankle through the third metatarsal head region, and a counter portion having an oblique axis extending from the region of the medial calcaneal tubercle towards the region of the head of the first metatarsal bone, said oblique axis offset at the region of the medial calcaneal tubercle to pass through the calcaneal tubercle.

3. A shoe comprising a central portion having a longitudinal axis extending from the region of the center of the ankle through the third metatarsal head region, and a toe portion having an oblique axis extending parallel to a line extending from the medial calcaneal tubercle to the head of the first metatarsal bone, said oblique axis offset sufficiently from the longitudinal axis of the central portion at the region of the medial cal-

canal tubercle to pass through the calcaneal tubercle.

4. A shoe comprising a central portion having a longitudinal axis extending from the region of the center of the ankle through the third metatarsal head region, said central portion having a longitudinal arch portion forming a peak located posterior to the scaphoid tubercle and approximately at the level of the ligamentous junction of the calcaneus with the scaphoid bone on the medial side and at the junction of the calcaneus with the cuboid bone on the lateral side.

5. The shoe of claim 4 provided with a counter portion having a posterior pillar which extends from the peak posteriorly to the region of the inferior medial calcaneal tubercle as a short slope, and is rounded as it passes under the tubercle.

6. The shoe of claim 4 having an anterior pillar which extends in a gradual slope from the peak forward to and under the head of the first metatarsal bone on the medial side and to the head of the fifth metatarsal bone on the lateral side.

7. A shoe comprising a central portion having a longitudinal axis extending from the region of the center of the ankle through the third metatarsal head region, a toe portion and an innersole, said shoe provided with a longitudinal arch portion forming a peak located approximately at the level of the ligamentous junction of the calcaneus with the scaphoid bone on the medial side and at the level of the junction of the calcaneus with the cuboid bone on the lateral side, and having an anterior pillar which extends in a gradual slope from the peak forward to the region of the head of the first metatarsal bone on the medial side and the region of the head of the fifth metatarsal bone on the lateral side, the longitudinal arch portion of the shoe, on the inner sole thereof having a recess in the medial marginal area beneath the region of the scaphoid bone to accommodate the downward projecting tubercle thereof.

8. A shoe comprising a central portion having a longitudinal axis extending from the region of the center of the ankle through the third metatarsal head region, and a counter portion having its longitudinal axis laterally displaced from the longitudinal axis of the central portion by a distance equal to the eccentricity of the calcaneal tubercle, said counter portion joined to said central portion with the medial side pared, and the lateral side filled at the junction margins to provide a smooth merger of the two portions.
